UNITED STATES PATENT OFFICE.

JAMES M. LONGAN, OF CHICOPEE, KANSAS, ASSIGNOR OF ONE-HALF TO WALLACE E. WRIGHT, OF CHICOPEE, KANSAS.

ORE WASHER AND SEPARATOR.

1,264,667.

Specification of Letters Patent. Patented Apr. 30, 1918.

Application filed August 8, 1917. Serial No. 185,072.

To all whom it may concern:

Be it known that I, JAMES M. LONGAN, a citizen of the United States, residing at Chicopee, in the county of Crawford and 5 State of Kansas, have invented a new and useful Ore Washer and Separator, of which the following is a specification.

The present invention relates to ore washers, separators and concentrators, and aims 10 to provide a novel and improved machine for washing various ores and separating the same from dirt and slime, in a thoroughly practical and efficient manner and with a continuous operation.

15 It is the object of the invention to provide a machine embodying a plurality of washing and concentrating pans or boards, and novel means for mounting the same for movement past a receiver or receivers for the discharge 20 of the ore thereinto, the pans or boards being agitated to concentrate the ores therein.

A further object of the invention is the provision of a machine of the nature indicated wherein the pans or boards are 25 mounted for circuitous movement to provide for a continuous operation, the unwashed ore being delivered onto the machine at one point, and water being supplied thereon at another point, so that the washing and separation take place as the pans are moved in 30 succession to the receiver to discharge thereinto.

The invention also has for its object the provision of an ore washer and separator of 35 the nature indicated embodying a novel assemblage of the component elements and novel actuating mechanism, whereby the operation of the machine will be carried out in a satisfactory manner, under various conditions.

40 With the foregoing and other objects in view, which will appear as the description proceeds, the invention resides in the combination and arrangement of parts and in 45 the details of construction hereinafter described and claimed, it being understood that changes in the precise embodiment of the invention herein disclosed can be made within the scope of what is claimed, without departing 50 from the spirit of the invention.

The invention is illustrated in the accompanying drawings, wherein:

Figure 1 is a plan view of the machine, 55 portions being broken away to show parts underneath.

Fig. 2 is a side elevation, portions being broken away.

Fig. 3 is a longitudinal section on the line 3-3 of Fig. 1.

Fig. 4 is a cross section on the line 4-4 60 of Fig. 2, parts being omitted.

Fig. 5 is a plan view of the parts shown in Fig. 4, portions being omitted.

Fig. 6 is an enlarged detail view of one of the catches. 65

Figs. 7 and 8 are plan views of modified forms of pans or boards used with different ores.

The machine embodies a suitable base 1 above which is disposed an inclined supporting frame 2 having its lower end hinged, 70 as at 3, to the base in order that the frame can be supported at various angles to suit various materials and ores. The upper end of the frame 2 is supported by props 4 or 75 other suitable means from the base.

The shaking or agitating frame 5 is mounted on the supporting frame 2 in a similarly inclined position for transverse vibratory movement, and this shaking frame 80 embodies transverse cleats or bars 6 seated on the frame 2, and longitudinal side bars 7 secured on the cleats 6. The cleats 6 have recesses 8 accommodating the side bars of the frame 2, permitting the frame 5 to have 85 a limited transverse movement. The frame 5 rests against a transverse plate 9 secured upon the frame 2, thereby preventing the shaking frame from sliding downwardly on 90 the supporting frame. 90

In order to shake the frame 5 transversely, reciprocating bars 10 are carried by the frame 2 at the opposite sides thereof and are provided at the opposite sides with reversed cams or wedges 11 working in the 95 recesses 8, and the cam bars 10 are connected by links or connecting rods 12 with cams or eccentrics 14 mounted on a transverse drive shaft 14 carried by the frame 2 near its upper end. Thus, when the drive shaft 14 100 is rotated, the connecting rods 12 will reciprocate the cam bars 10, thereby actuating the cams or wedges 11 which vibrate or shake the frame 5 transversely and parts carried thereby. 105

The side bars of the frame 5 are provided with upstanding longitudinal guides 16 for the ends of the transverse elongated washing and separating boards or pans 17, which can be constructed of wood or other suitable ma- 110

terial. As illustrated, said pans are each of wood having on the upper surface the sheet metal plate 19 provided at one edge with an outwardly curved lip or riffle 20. 5 The ends of the pan or board are provided with tongues 18 of reduced width to work in the guides 16 with the riffle 20 of the pan at the lowermost edge thereof. The riffles 20 of the pan serve to retain the ore or heavier 10 material within the pans, but permit the dirt and lighter materials to be washed from one pan to another with the water as it flows downwardly over the series of pans, the riffles 20 also overlapping the next lower 15 pans to discharge the materials from one pan to another toward the lower end of the machine.

As a means for giving the pans a greater 20 inclination transversely thereof when they reach the upper end of the shaking frame on which the pans move upwardly, guides or rails 21 are pivotally connected by links 22 or otherwise with the frame 5 near the upper end thereof, and extend over the upper 25 end of said frame, being arranged at a greater angle of inclination relative to the base 1, and at an acute angle with the frame 5. The upper ends of the guides 21 are 30 adjustably supported by adjusting screws 23 carried thereby and resting on the frame 5, or other suitable means can be used for adjusting said guides. The frames 2 and 5, as above explained, can be adjusted to different 35 angles of inclination due to the hinging of the frame 2 to the base, and the guides 21 being hingedly connected with the frame 5, can in turn be adjusted at various angles 40 of inclination relatively to the frames according to the materials being worked. The guides 21 extend upwardly at an angle from the upper ends of the guides 16, so that the pans 17 as they are moved upwardly, move 45 from the guides 16 into the guides 21, and in doing so, will be given a greater angle of transverse inclination longitudinally of 50 the machine, to dump the ore into the receiver, as will hereinafter more fully appear. The guides 21 have grooves 24 for receiving the tongues 18 of the pans and said 55 guides have cut-away portions 25 permitting the tongues 18 to move downwardly, whereby to transfer the pans to the returning device. The pans when they are moved 60 between the guides 21 have their tongues 18 moved over cleats 26 carried by the guides beyond the recesses or cut-away portions 25, thereby supporting the upper edges of the pans until the tongues 18 are in a position to move downwardly, thereby causing 65 the lower edge of the pan to drop, as seen in Fig. 3, while the upper edge is supported on the cleats 26.

The returning device for the pans embodies endless belts 27 trained around pulleys 28 carried by the upper end of the

frame 2, as at 29, and also trained around pulley wheels 30 carried by a transverse shaft 31 journaled to the frame 2 at the lower end thereof. The upper runs of the belts 27 move downwardly underneath the 70 upwardly moving set of pans carried by the shaking frame 5, so that when the uppermost pan drops downwardly from between the guides 21, it seats on the belts 27, which convey the pan downwardly underneath the active set of pans to the lower end of the frame 5, where the pan is limited in its movement by suitable stops 33 carried by said frame. 75

The pan which is returned to the lower 80 end of the frame 5 is transferred back into the guides 16 at the lower ends thereof, by means of a pair of longitudinal lift bars 34 85 slidable longitudinally on the cleats 6 within guides 35 thereon, said bars 34 being provided with cams 36 to move onto the cleats 6 when said bars are moved downwardly, thereby raising said bars. Said bars are normally slightly below the plane of the upper runs of the belts 27, but when said bars are moved downwardly and raised by the cams 36, the bars are raised above said plane. The pan at the lower end of the machine which rests against the stop 33 will, therefore, be raised by said bars into the plane of the guides 16 for upward movement into said guides. The bars are also raised at their upper ends to receive the pan which passes from between the guides 21, as explained more in detail hereinafter. These 90 bars 34 form a part of an intermittently reciprocated trip or actuating mechanism embodying a transverse bar 38 mounted for longitudinal movement of the machine below the frame 5 and above the frame 2, and connected by links 37 with the bars 34 to reciprocate said bars. Cords or other flexible elements 39 are connected to the bar 38 and extend over guides 40 at the upper end of the frame 2 and have suitable weights 41 suspended from their free terminals, whereby the weights normally move the bar 38 and parts connected therewith upwardly to normal position when released. The bar 38 and parts connected thereto are moved 95 downwardly intermittently by means of cords or other flexible elements 42 connected to said bar and to a transverse winding shaft 43 carried by the frame 2 for winding up the cords 42, whereby to pull the bar 38 100 downwardly. This shaft 43 is provided with a star wheel 44 thereon disposed between the belts 32 which connect the shafts 105 14 and 31 to drive the belts 27. The belts 32 are connected by a series of transverse cleats 110 45 providing a rack to mesh with the star wheel 44 and rotate the shaft 43 to wind up the cords 42 once during each circuitous movement of the belts 32. Thus, when the cleats 45 pass the star wheel 44, the shaft 115 120

125 130

43 is rotated to wind up the cords 42, thus pulling the bar 38 and parts connected thereto downwardly, and after the cleats 45 have passed the star wheel 44, the bar 38 is released, so that the weights 41 pull it back to normal position.

Upstanding plates 46 are secured to the ends of the bar 38 and have connected thereto links 47 extending behind the links 22 and 10 connected at their upper ends to a transverse strip 48 sliding on the guides 22. This strip 48 is reciprocated with the bar 38, and assists in the removal of the pans from said guides.

A transverse bar 49 is secured upon the 15 plates 46 above the guides 16 and frame 5, and have secured thereon a receiver or collecting pan 50 which has its upper receiving edge so arranged as to move below the riffles 20 in succession as the pans are fed upwardly. The receiver 50 has a discharge 20 spout 51 extending to one side.

As illustrated, a single receiver is employed, but it will be readily appreciated that a number of receivers can be used side 25 by side, or at different positions when a multiple separation of the ore is desired. Various forms of pans can also be used, according to the material being worked and other conditions. The pans shown in Figs. 1 and 30 3 are of simple or plain construction for ordinary use, whereas the pan shown in Fig. 7 is provided with oblique corrugations 60 and partition or separating cleats 61, for use with certain kinds of material, when the action 35 of the corrugations adds efficiency to the operation. It will be noted that the corrugations will serve to direct the ore transversely of the machine during the shaking and upward movement of the pan, whereby 40 to discharge the desired ore into the receiver. The receivers can, therefore, be of restricted width, as seen in Fig. 1, to receive the ores from one point of the pans only, thereby providing for a more thorough separation 45 of the material. Fig. 8 illustrates still another form of pan having the cleats 61 and drain apertures 62 adjacent to the riffles 20. These and other forms of pans can be used as required.

50 In order to move the pans upwardly on the shaking frame 5, bars 52 are secured to the bar 49 and extend downwardly along the guides 16 over the tongues 18 of the respective pans, and catches 53 are pivoted to the 55 lower ends of the bars 52 to drop into engagement with the tongues 18. Said catches are reciprocated back and forth with the bar 38, whereby when the bar 38 is moved downwardly, the catches 53 will engage the 60 tongues 18 of the pan which is raised by the lift bars 34, the return movement of the bar 38, therefore, moving the lowermost pan with the catches 53 upwardly into the guides 16, thereby advancing out of the pans on the 65 shaking frame. Catches 54 are carried by

the shaking frame near the lower end thereof, to engage the tongues 18 and prevent the downward movement of the pans, especially when the bars 52 are moved downwardly. The bars 52 work under guides 55 carried by 70 the frame 5, while the catches 54 work under guides 56.

The operation of the machine is as follows: The material to be separated is delivered onto the pans at the lower portion 75 of the machine in any suitable manner, and water is sprinkled or otherwise supplied onto the pans to wash the dirt and lighter materials downwardly. During the operation of the machine, the cam bars 11 will be 80 reciprocated continuously by the rotation of the cams 13 with the shaft 14, thus shaking the frame 5 transversely. This will shake the pans longitudinally of themselves, whereby to facilitate the washing of 85 the lighter materials from the ore, which concentrates in the pans adjacent to the riffles, serving to retain the ore. The water and lighter materials will flow from one pan to another over the riffles down the machine, 90 thereby washing the ore. The pan 17 which is in the guides 21 is arranged at greater angle and its riffle overhangs the receiving portion of the receiver 50, so that the ore will be discharged from said pan into the 95 receiver due to the transverse movement of said pan, the lighter materials having been previously washed from said pan during its upward step by step movement. At intervals, the cleats or rack 45 of the belt 32 will 100 engage the star wheel 44 and rotate the shaft 43 to wind the cords 42 thereon, thereby moving the bar 38 downwardly, together with the links 47 and strip 48, bar 49 and receiver 50, and bars 52 and catches 53. During such downward movement of the bar 38, the bars 34 are also moved downwardly, whereby to lift the empty pan at the lower end of the machine, which has its tongues 18 engaged by the catches 53. The receiver 110 50 in being moved downwardly, will have its receiving edge moved past and under the riffle 20 of the next pan. Now, when the cleats 45 have moved past the star wheel 44, thus releasing the bar 38, said bar is returned upwardly by the weights 41 or equivalent means. The catches 53 being moved upwardly will carry the lowermost pan with them into the guides 16 from the bars 34, and the lowermost pan will push 115 120 the other pans ahead of it upwardly in the guides 16 and 21. The receiver 50 also moves upwardly with the pans, and the strip 48 which was previously moved downwardly along the guides 21 over the pan 17, which previously discharged into the receiver, will move upwardly with said pan as the pan moves over the cleats 26, thus holding the pan on the cleats 26 momentarily, until the 125 tongues 18 of the pan can drop through the 130

cut-away portions 25. The lower edge of the pan, therefore, drops first, as seen in dotted line in Fig. 3, onto the bars 34, and the strip 48 passes over the upper edge of the pan off 5 of the same. When the parts have returned to normal position, the bars 34 in being lowered let the lower edge of the dropped pan rest on the belts 27 which carry the pan downwardly to the stops 33, said pan being 10 cleaned out since the ore was delivered to the receiver, and the dropping of the pan will also further clean it out. The pan which is moved ahead of the receiver in moving from the guides 16 into the guides 21 will 15 be given a greater angle of inclination, thereby assisting in the discharge of ore into the receiver in addition to the transverse shaking movement of the pans. The transverse shaking movement of the pans is 20 continued in the meantime, and the pans remain in their longitudinal position until the cleats 45 again engage the star wheel 44, when the operation is repeated as before. The pans move through a circuit, being 25 moved upwardly in a series to and past the receiver, and then returned to the lower end to again be moved up in regular order. This provides for a continuous operation of the machine, and a steady flow of material can 30 be delivered onto the machine. Each pan during its shaking movement is fed upwardly step by step to finally discharge into the receiver, and is then returned back to receive another supply of material. The 35 pans move up the incline during their shaking movement, whereby the lighter materials are washed downwardly from one pan to the other to be discharged from the lower-most pan. After the dirt and lighter materials 40 are washed from the ore, the ore is discharged into the receiver, thus completely emptying the pan automatically, whereby there is neither an accumulation of ore nor waste material in the machine. Consequently, 45 the machine need not be stopped for cleaning, and the separation of ore will be uniform, due to the fact that each pan is a unit in itself, first receiving the material, then having the dirt and lighter materials washed therefrom, then discharging the concentrated ore into the receiver, and then returning back to position to receive more material.

Having thus described the invention, 55 what is claimed as new is:

1. A separator embodying a movable receiver, a separating pan movable to and past the receiver to discharge thereinto, and means for advancing the pan and reciprocating the receiver to advance with and then be returned from the pan, and for agitating the pan.

2. A separator embodying a movable receiver, a separating pan movable to and past 65 the receiver to discharge thereinto, means

for moving the pan to discharge into the receiver, and means for advancing the pan and reciprocating the receiver to move with the pan when it is advanced and to then be returned.

3. A separator embodying a movable receiver, a separating pan movable to and past the receiver to discharge thereinto, means for moving the pan to discharge into the receiver, and means for advancing the pan 75 and reciprocating the receiver to advance with and then be returned from the pan and for shaking the pan.

4. A separator embodying a receiver, a series of separating pans, and means for 80 moving said pans under the receiver in succession, lowering the receiver to receiving position and tilting the pans after moving from under the receiver to discharge thereinto.

5. A separator embodying a receiver, a series of separating pans having riffles, and means for agitating the pans to discharge the lighter materials over said riffles from one pan into another, for moving the pans 90 under the receiver in succession, for lowering the receiver to receiving position and tilting the pans after moving under the receiver to discharge the concentrates over said riffles into the receiver.

6. A separator embodying a movable receiver, a series of separating pans movable past the receiver to discharge thereinto, and means for advancing the pans to discharge in succession into the receiver and for reciprocating the receiver to move with the successive pans when advanced.

7. A separator embodying a movable receiver a series of separating pans movable past the receiver to discharge thereinto, and 105 means for advancing the pans to discharge in succession into the receiver and for reciprocating the receiver to move with the successive pans when advanced and for shaking said pans and receiver.

8. A separator embodying a receiver, a series of separating pans, means for guiding the pans in an inclined position past the receiver and for tilting the pans to incline them further in the same direction so as to 115 discharge into the receiver, and means for agitating the pans, lowering the receiver to receiving position and moving the pans upwardly along the guiding means.

9. A separator of the construction specified in claim 8, and including means for returning the pans from the upper to the lower end of the guiding means for circuitous movement.

10. A separator embodying a movable receiver, a series of separating pans, means for guiding said pans up an incline to the receiver and for increasing the inclination of the pans to discharge into the receiver, means for returning the pans underneath the 130

series from the upper end of said guiding means to the lower end thereof, and reciprocatory means for reciprocating the receiver to be advanced with the pans in succession and advancing the pans up the guiding means.

11. A separator embodying a movable receiver, a series of separating pans, means for guiding said pans up an incline to the receiver and for increasing the inclination of the pans to discharge into the receiver, means for returning the pans from the upper end of the guiding means under the series of pans to the lower end of said guiding means, means for shaking the pans, and reciprocatory means for reciprocating the receiver to be advanced with the pans in succession, for raising the returned pans to move into the guiding means and for advancing the pans in the guiding means.

12. A separator embodying a supporting frame, a shaking frame movable transversely thereon and having inclined guiding

means, separating pans movable up said guiding means, reciprocatory means carried by the shaking frame movable longitudinally thereof, a receiver carried by said reciprocatory means, the guiding means having an inclined portion to further tilt the pans to discharge into the receiver, and to permit the pans to drop, means for returning the dropped pans from the upper end of the guiding means to the lower end thereof, means for moving the shaking frame transversely, and means operated by said reciprocatory means for raising the pans from the returning means to move into the guiding means and for moving the pans step by step upwardly in the guiding means.

In testimony that I claim the foregoing as my own, I have hereto affixed my signature in the presence of two witnesses.

JAMES M. LONGAN.
